[57] CLAIM

The ornamental design for an extruded section for display racks, as shown and described.

DESCRIPTION

FIG. 1 is a top, front, right-side perspective view of an extruded section for display racks showing our new design, the extruded section for display racks being of indeterminate length;

FIG. 2 is a top front, left-side perspective view thereof; FIG. 3 is a front elevational view, the rear being identical thereto;

FIG. 4 is a top plan view thereof;

FIG. 5 is a left side elevational view, the right side being identical thereto; and,

FIG. 6 is a bottom plan view thereof.

*FIG. 1**FIG. 2*FIG. 3

FIG. 4

FIG. 5

FIG. 6
